SPOON

Hans Reichl, Seattle, Wash., assignor to
E. Kenneth Rogers, Oakland, Calif.

Application February 11, 1952, Serial No. 18,463

Term of patent 14 years

(Cl. D54—12)

To all whom it may concern:

Be it known that I, Hans Reichl, a citizen of the United States, residing in the city of Seattle, county of King, State of Washington, have invented a new, original, and ornamental Design for a Spoon, of which the following is a specification, reference being had to the accompanying drawing, forming part thereof.

In the drawing:

Fig. 1 is a front elevational view of the spoon showing the essential features of my new design in full lines,

Fig. 2 is a rear elevation of the same.

Fig. 3 is a cross-sectional view taken on the line 3—3 of Fig. 1, and

Fig. 4 is a cross-sectional view taken on the line 4—4 of Fig. 1.

I claim:

The ornamental design for a spoon, as shown and described.

HANS REICHL.
